UNITED STATES PATENT OFFICE.

STEPHEN D. GOUGH, OF SEATTLE, WASHINGTON.

HAIR-ointment.

1,365,981.

Specification of Letters Patent.

Patented Jan. 18, 1921.

No Drawing.

Application filed December 17, 1918. Serial No. 267,146.

To all whom it may concern:

Be it known that I, STEPHEN D. GOUGH, a citizen of the United States, residing at Seattle, in the county of King and State of Washington, have invented certain new and useful Improvements in Hair-Ointments; and I do hereby declare the following to be a full, clear, and exact description of the invention, such as will enable others skilled 5 in the art to which it appertains to make and use the same.

This invention relates to salves, and more particularly to a salve specially adapted for use as a hair tonic.

15 The primary object of the invention is to provide a salve or ointment which is specially adapted for softening the scalp and strengthening the hair roots so as to encourage growth of the hair. I have found that 20 a salve well adapted for this purpose may be made by combining turpentine, wood alcohol, beeswax, lard, and carbolic acid in proper proportions. In making this salve, I employ the above stated ingredients in approximately the proportions given in the 25 following example:—

Turpentine	2 parts,
Wood (methyl) alcohol	3 parts,
Beeswax	4 parts,
Lard	6 parts,
Carbolic acid	5 parts.

In preparing the salve, the wax and lard

are first melted together, after which the other ingredients are added in order, being 35 thoroughly mixed and stirred as they are added so as to insure thorough and intimate combining of the various ingredients. The mixture thus produced is permitted to cool and forms a salve which may be readily 40 applied by being thoroughly rubbed into the scalp.

I have found by experience that this salve is very efficient and serves to quickly soften and clean the scalp so as to place it in a 45 healthy condition, as well as furnishing nourishment for the roots of the hair so as to encourage hair growth.

What I claim is:

1. An ointment comprising a mixture of 50 turpentine, wood alcohol, carbolic acid and a fatty vehicle in such proportions as to form a hair ointment.

2. A hair ointment comprising a mixture of about 2 parts of turpentine, about 3 55 parts of wood alcohol, about 10 parts of a fatty waxy vehicle and about 5 parts of carbolic acid.

In testimony whereof I affix my signature in presence of two witnesses.

STEPHEN D. *X* GOUGH.
